UNITED STATES PATENT OFFICE.

JONATHAN HANDY AND WILLIAM D. SHERMAN, OF NEW BEDFORD,
MASSACHUSETTS.

WAGON-SEAT RISER.

SPECIFICATION forming part of Letters Patent No. 434,183, dated August 12, 1890.

Application filed May 2, 1890. Serial No. 350,351. (No model.)

To all whom it may concern:

Be it known that we, JONATHAN HANDY and WILLIAM D. SHERMAN, citizens of the United States, residing at New Bedford, in the county of Bristol and State of Massachusetts, have invented certain new and useful Improvements in Wagon-Seat Risers, of which the following is a specification.

Our invention relates to wagon-seats, and particularly to that part which is commonly called the "riser;" and its object is to produce a seat-riser by means of which the seat may be securely clamped to the wagon-box.

Heretofore wagon-seat risers have been constructed with feet to rest and slide on the edge of the wagon-box, or the risers have been provided with a pin to enter holes in the edge of the wagon-box. Both of these forms are objectionable, for the reason that a sudden jolt is liable to throw the seat from its position, or a sudden start of the team is liable to throw the rear seat and its occupants over backward to the ground.

The accompanying drawings illustrate our invention, in which—

Figure 1 represents a view in perspective of our improved seat-riser; and Fig. 2 represents a view in cross - section of the same, showing the construction and operation of the clamping device.

Similar letters refer to similar parts throughout the several views.

a a represent the feet of the riser, which

rest on and embrace the top edge of the wagon-box. One of the legs of the riser is composed of two parts *b* and *h*. The part *b* is pivoted to the part *h* at *c*. A bolt *e* passes through the parts *b* and *h*, and is provided with the hand-nut *d*, and the riser is clamped to the edge of the wagon-box by drawing the parts *b* and *h* together by means of the bolt *e* and hand-nut *d*. The inside surface of the clamping-foot is preferably corrugated, as at *g*, in order to take a firmer hold on the edge of the wagon-box. It is designed that the riser on each end of the wagon-seat shall be provided with a clamping-foot.

Having thus described our invention, what we claim, and desire to secure by Letters Patent, is—

A wagon-seat riser composed of cast metal, adapted to be secured to the seat by bolts or screws, and having three feet adapted to rest on and embrace the edge of the wagon-box, and having the middle foot composed of the part *h*, having the part *b* pivoted thereto, and provided with the bolt *e* and hand-nut *d*, whereby the corrugated projections *g* are caused to clamp the edge of the wagon-box and hold the seat firmly in position, as shown and described.

JONATHAN HANDY.
WILLIAM D. SHERMAN.
